[57] CLAIM

The ornamental design for a fishing rod holder, substantially as shown and described.

DESCRIPTION

FIG. 1 is an isometric view of a fishing rod holder embodying the design of the present invention.

FIG. 2 is a right side elevational view of the fishing rod holder illustrated in FIG. 1.

FIG. 3 is a rear elevational view of the fishing rod holder illustrated in FIG. 1.

FIG. 4 is a left side elevational view of the fishing rod holder illustrated in FIG. 1.

FIG. 5 is a front elevational view of the fishing rod holder illustrated in FIG. 1.

FIG. 6 is a top plan view of the fishing rod holder illustrated in FIG. 1.

FIG. 7 is a bottom plan view of the fishing rod holder illustrated in FIG. 1.

FIG. 8 is a right side isometric view of a further embodiment of a fishing rod holder embodying the design of the present invention.

FIG. 9 is a left side isometric view of the fishing rod holder illustrated in FIG. 8.

FIG. 1.

FIG. 2.

FIG. 3.

FIG. 4.

FIG. 5.

FIG. 6.

FIG. 7.

FIG.8.

FIG.9.
